[57] CLAIM

The ornamental design for a torque wrench, as shown
and described.

DESCRIPTION

FIG. 1 is a top plan view of a torque wrench showing
my new design;

FIG. 2 is a front end elevation view thereof;
FIG. 3 is a side elevation view thereof, the opposite side
being a mirror image of that shown;

FIG. 4 is a rear end elevation view thereof; and
FIG. 5 is a bottom plan view thereof.
